CLAIM

The ornamental design for an oral care implement package, as shown and described.

DESCRIPTION

FIG. 1 is a front perspective view of a first embodiment of the new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a front perspective view of a second embodiment of the new design;

FIG. 10 is a rear perspective view thereof;

FIG. 11 is a front view thereof;

FIG. 12 is a rear view thereof;

FIG. 13 is a right side view thereof;

FIG. 14 is a left side view thereof;

FIG. 15 is a top view thereof; and,

FIG. 16 is a bottom view thereof.

The broken lines in FIGS. 2 and 4 represent the claimed tear strip portion of the package. The broken lines in 9-14 and 16 illustrate unclaimed environment only and form no part of the claimed design. The oblique line shading 1, 3, and 5 represents a transparent or translucent surface.

1 Claim, 12 Drawing Sheets
